ATTY'S

UNITED STATES PATENT OFFICE.

GEORGE P. BUTLER, OF NEW YORK, N. Y.

DESIGN FOR A CIGARETTE-BOX.

SPECIFICATION forming part of Design No. 35,865, dated April 15, 1902.

Application filed March 1, 1899. Serial No. 707,410. Term of patent 14 years.

To all whom it may concern:

Be it known that I, GEORGE P. BUTLER, a citizen of the United States, and a resident of the city of New York, in the county and State of New York, have invented a new and original Design for Cigarette-Boxes, of which the following is a specification.

My invention, as shown in the drawing, consists in a new design for a cigarette-box.

10 The design consists of a representation upon the box adapted to hold the cigarettes of a bunch of cigarettes bound by a band or ribbon.

What I claim as new, and desire to secure by Letters Patent, is—

The design for a cigarette-box as herein 15 shown and described.

In testimony whereof I have signed my name to this specification in the presence of two subscribing witnesses.

GEORGE P. BUTLER.
